PLASTIC TRAVELER

William M. Camp, Glen Ridge, N. J., assignor to
 The Clark Thread Company, Newark, N. J., a
 corporation of New Jersey

Application March 31, 1942, Serial No. 437,044

3 Claims. (Cl. 57—125)

This invention relates to travelers which are used on spinning and twisting frames in the textile industry.

In the past, travelers have been made of either steel or bronze, the bronze being used mostly on wet twisting, where the presence of water makes it undesirable to use steel. These travelers rotate around the ring at a high speed, and in the case of twisting where the drag on the traveler is heavy it is necessary to provide lubrication between the traveler and the ring, this taking the form of an oil or grease. Even under conditions of good lubrication, wear takes place on the traveler and also on the ring and the fine particles of metal which are worn off become embedded in the grease and are subsequently oxidized and thus form visible stains on the yarns or threads. These stains consist of oxides, carbonates, soaps, etc., of the respective traveler and ring metals, and are very difficult to remove in the ordinary processes of kier-boiling and bleaching.

Many attempts have been made to make travelers of materials, other than steel and bronze, using materials including hard rubber and glass. These materials, however, have not been satisfactory because of their brittleness and poor resistance against wear.

It is an object of this invention to provide a traveler possessing properties which have long been sought, including the following:

1. A longer life than steel or bronze travelers.
2. Requiring less lubrication than steel or bronze travelers or no lubrication.
3. Producing little or no wear on the steel ring and therefore obviating the contamination of the yarn or thread referred to above.
4. Corrosion resistance, to avoid corrosion in wet twisting.

The invention will be further described by reference to the accompanying drawing, in which

Fig. 1 shows one type of conventional ring with a traveler mounted thereon;

Fig. 2 shows a traveler for use with the ring of Fig. 1;

Fig. 3 shows another type of conventional ring with a traveler mounted thereon; and

Fig. 4 shows a traveler for use with the ring shown in Fig. 3.

In accordance with the generic aspect of this invention, travelers are made from polymers of esters of acrylic acid. In accordance with a more specific aspect of the invention, travelers

are made from the polymers of esters of methyl acrylic acid. The preferred species of ester is the methyl ester.

The details of preparing the above mentioned polymers, including the use of various plasticizers, and the control of the degree of polymerization are subject to considerable variation and may be varied, in the light of this invention, to secure polymers adapted to meet the preferred criteria of this invention. These are, briefly, a combination of resiliency, toughness, shock resistance, abrasion resistance and corrosion resistance. Resiliency is required because the jaws of the traveler are usually sprung apart in mounting it on the ring. Toughness and impact, or shock resistance, are required to avoid undue breakage. Abrasion resistance is desired to avoid undue wear. Corrosion resistance is desired to avoid corrosion in wet twisting.

Having obtained the acrylic polymer possessing the desired properties, the traveler is made therefrom by molding from molding material or machining from extruded or otherwise pre-formed stock. No details as to the structural form of the traveler are necessary, since the various shapes and forms of travelers are well known. Nor need any details of molding, machining or extruding be given since the art of molding, machining and extruding polymers of acrylic acid and its derivatives is well known.

However, in some cases, it may be desired to provide a traveler having a metallic core and a wearing surface comprising or composed essentially of a polymer of acrylic acid esters as above described. This may be done, for example, by using a steel or alloy core or insert and molding the acrylic polymer composition around said core so that the latter is embedded in the resulting molded product.

The term "acrylic polymer" as herein used means a polymer of an ester of acrylic acid or methyl acrylic acid.

I claim:

1. A traveler the wearing surface of which comprises an acrylic polymer.
2. A traveler composed essentially of an acrylic polymer.
3. A traveler having a metallic core and a wearing surface composed essentially of an acrylic polymer.

WILLIAM M. CAMP.
